SHINGLE CONSTRUCTION AND COMPOSITION

Filed July 31, 1928

UNITED STATES PATENT OFFICE

GEORGE B. STRYKER, JR., OF MEMPHIS, TENNESSEE, ASSIGNOR TO THE WEATHER-PROOF PRODUCTS COMPANY, OF MEMPHIS, TENNESSEE, A CORPORATION OF TENNESSEE

SHINGLE CONSTRUCTION AND COMPOSITION

Application filed July 31, 1928. Serial No. 296,603.

The present invention relates to a composite unit for building or construction purposes such as a shingle or the like, formed of two individual members or elements firmly and permanently united and each possessing different physical qualities which are all desirable in material of that class but which qualities have been found difficult to combine in a practical manner.

For this reason the present invention contemplates the formation of two elements one of which constitutes the core or base and is porous, soft, tenacious, light and forms a heat and sound insulator, the other element forming a cover member and being hard and compact, which makes it hard and weatherproof, impenetrable by water and a perfect electric insulator. These two elements are intimately and firmly united during the process of manufacture so as to form an inseparable unit, easy to pack and ship on account of the simple shape, preferably rectangular.

Some of the advantages possessed by this shingle unit may here be enumerated, viz.: Its lightness as compared with other shingles with a very hard upper surface. As one element is very light and the other heavy, both having approximately the same volume, the compounded unit will be of medium weight.

The great porousness of the base element makes the shingle soundproof, so that the clatter of rain or hail on a roof will not be heard in the house, and the hard top surface of the cover element provides a good wearing shingle; while the toughness and tenacity of the one element and the great hardness of the other provides a shingle unit of great strength, which will be able to withstand a great deal of abuse in handling.

As the surrounding flanges of the cover element tightly grip the edges of the base, the two elements are firmly united and the flanges are higher than the thickness of the base element, seeping water cannot reach the latter when the shingles are laid.

In the accompanying drawing one embodiment of the invention is illustrated, and:

Figure 1 is a plan view of the base element of the shingle; and,

Figure 2 is an end view of Figure 1;

Figure 3 an under plan view of the top or cover element of the shingle; and,

Figure 4 an end view of Figure 3;

Figure 5 is a bottom plan view of the assembled shingle;

Figure 6 a transverse section along line 6-6 of Figure 5;

Figure 7 a longitudinal section along line 7-7 of Figure 5;

Figure 8 is a fragmentary plan view of a roof laid with these shingles; and,

Figure 9 a fragmentary section along line 9-9 of Figure 8.

Reference numeral 10 represents the base or core element and numeral 11 the top or cover element. By means of the marginal depending flanges 12 the top element 11 grips tightly the edges of the base element 10 on three sides. To insure still further hold between the two elements, the side edges of the base element are preferably provided with indentations or notches as at 18, while the flanges of the top element have corresponding sharp projections 14 engaging said notches. The lower end of the base element is slightly tapered as from 15 to 16 for the purpose of increasing the flange 18 thickness of the top element, thereby giving greater strength and also preventing water from reaching the base element. For the same reason the flanges 12 are made slightly higher, as at 18, than the thickness of the pad or base element, which preferably has uniform thickness. In this manner when the shingle is laid the bottom surface of the pad or base element will be raised above the supporting structure.

As best seen in Figure 5 of the drawing the finished shingle is preferably rectangular, that is to say, the top element has parallel side edges which merge into the edges of the upper portion 17 of the base element, while the remainder of the latter has the same contour as the inner side of the flanges 12.

The body portion 19 of the top or cover element 11 tapers slightly from one end.

to the other, being thickest at the lower end as at 18 where it is of the same or greater thickness than the base element, while running out to a knife edge a little short of the top edge of the base element 10 or about midway between said edge and the notches 14. At 22 are shown nail holes in the top element for securing the shingles in position.

10 In Figures 8 and 9 is illustrated the preferable manner of laying the shingles. A tier of units A is first nailed fast as at 22 and positioned with the butt-ends 23 lowermost, in a straight line in the usual manner. The next tier B is then placed on top of the first with its line of butt-ends 23 about six inches from the first butt end line or about even with points 15 of Figure 1. This then provides the exposed or "weather" 15 portion of units A. At the same time the side edges of the units in tier B are displaced about one-third of the width of the shingle from the side edges of tier A as seen in Figure 8. This gives a staggered 20 line of exposed side edges. Similarly the third and fourth units of shingle units are laid and nailed fast to produce the assembled effect indicated.

The preferred size of a shingle unit is 30 six inches by fourteen inches (6" x 14") distributed as follows: 2" from the upper edge to the notch 13; 6" between said notch and the point 15; and 6" below the latter. In this manner there will always be three 35 thicknesses of shingle near its upper and lower edge and in the middle of 2" length, while 8" will have double thickness and only 6" will be exposed.

The manner of manufacturing these shingle units is fully disclosed in my co-pending application: "method of making shingles"; Serial No. 296,605; filed simultaneously herewith, and will only be gone into briefly here below.

45 The porous base or core element 10 is first produced from suitable fibrous material, preferably waste paper and cotton fibre, which is compressed and shaped into a pad of substantially uniform thickness and having a contour as shown in Figures 1 and 2. A plastic mass of cement, fibre, lime, and clay, or any other similar material possessing the same properties, is then dissolved and thoroughly mixed in water. It is there- 50 upon poured over the finished pad or base element and subjected to high pressure so that the mass is spread compactly over one surface and around three edges of the base element. In this manner element 11 forms a 55 hardened envelope over the base element 10 constituting a complete unit therewith.

As the shingle unit thus consists of two 60 distinct elements each possessing its own characteristic properties which are not in any manner changed or influenced by the

union, the pad or base element, through its porosity will thus provide protection against heat, cold and sound disturbances, while the top or cover element protects the roof from the influences of all changing weather conditions, such as rain, hail, snow as well as electric disturbances, on account of it being dielectric.

The thick lower or butt end of the shingle unit will cause considerable retardation 75 of rain water flowing down a roof, as the terraced roof now will create actual cascades at each tier of shingle units.

The increased thickness both in the middle and at the sides of the "weather" or exposed portion of the cover element, considerably increases the wearing and lasting qualities of this shingle unit.

This shingle unit combines lightness with great strength and may be easily cut or 85 sawed to suit conditions.

It is to be understood that the invention as here disclosed is not limited to the details of construction shown and described and that these may be varied widely without departing from the spirit of the invention as defined by the claims.

What I claim as new is:

1. A composite shingle comprising a base member and a cover member; the base member consisting of a fibrous heat-insulating material of substantially uniform thickness and provided with notched edges; and the cover member consisting of a fire and waterproof material of tapering length section with depending flanges along both side edges and its thick end edge, said flanges being adapted to tightly grip the corresponding edges of said base member and engaging said notches, thereby holding said members tightly together to form a permanent unit.

2. A composite shingle comprising, a base member and a cover member, the base member consisting of a fibrous heat insulating material of substantially uniform thickness and provided with notched edges, and the cover member consisting of waterproof material having depending flanges along both side edges and its butt end, said flanges being adapted to tightly grip the corresponding edges of said base member and engaging said notches, thereby holding said members tightly together to form a permanent unit.

3. A composite shingle comprising a base member and a top member, said top member having depending flanges along its sides and butt edge providing a central recess between said flanges, said base member being thinner than the depth of said recess and fitting tightly between said flanges against the top of the recess, whereby the base member will be spaced from the bottom plane of the flanges, substantially as set forth.

4. A composite shingle comprising a base member and a cover member, the cover member having depending flanges along its sides and butt end providing a central recess between said flanges, the edges of said base member fitting tightly between said flanges, and said side flanges being provided with co-operating interlocking means.

5
10 In witness whereof, I have hereunto set my hand at Washington, District of Columbia, this twenty-seven day of July, A. D. nineteen hundred and twenty-eight.
